(57) **CLAIM**

The ornamental design for a “base for display apparatus,” as shown and described.

DESCRIPTION

FIG. 1 is a perspective view for a base for display apparatus of my new design;

FIG. 2 is a top plan view thereof;

FIG. 3 is a side elevational view thereof with each of the remaining four sides being identical;

FIG. 4 is a bottom plan view thereof; and,

FIG. 5 is an exploded perspective view illustrating an insert into a container thereof, the insert and container forming the base for display apparatus.
